UNITED STATES PATENT OFFICE.

SAMUEL B. WILLIAMS, JR., OF BROOKLYN, NEW YORK, ASSIGNOR TO WESTERN ELECTRIC COMPANY, INCORPORATED, OF NEW YORK, N. Y., A CORPORATION OF NEW YORK.

CARRIER-WAVE COMMUNICATING SYSTEM.

Application filed April 1, 1922. Serial No. 548,681.

To all whom it may concern:

Be it known that I, SAMUEL B. WILLIAMS, Jr., a citizen of the United States, residing at Brooklyn, in the county of Kings, State 5 of New York, have invented certain new and useful Improvements in Carrier-Wave Communicating Systems, of which the following is a full, clear, concise, and exact description.

10 This invention relates to an improved communicating system, and more particularly to a communicating system of the type in which carrier waves or oscillations, either free or guided, are employed as the medium 15 for conveying energy for effecting the operation and control of electric signaling, controlling and communicating apparatus located at separated points in the system. The invention especially relates to a system in 20 which carrier currents, in the form of high frequency waves guided upon wires, are used as the medium of electrical connection between the electrical devices and apparatuses located at different points in the system. 25 These carrier currents are assigned such frequencies that they are non-interfering with one another, so that each carrier serves as a separate and distinct connecting medium superposed upon the line or conductor 30 over which the carrier is transmitted. Each of the carriers is modulated in accordance with the voice currents or other signaling or controlling currents that are to be carried. The carriers thus modulated are transmitted 35 over the toll or long distance line and are passed through individual receiving arrangements, each of which is selective of one carrier frequency to the exclusion of the others, and each of which serves to reproduce from the modulated carrier the voice or signal currents with which the carrier was modulated at the distant station.

40 The apparatus which is used to transmit and receive by means of any one high frequency wave as distinguished from that which is used for transmitting and receiving by means of a wave of a different frequency, is commonly known as a high frequency channel, or frequency selective channel.

45 In the type of carrier communicating system to which the present invention particularly relates, a toll line or long distance line having associated with it a number of toll stations is provided at each station with

such high frequency channel terminal apparatus as is necessary to give each station access for calling and communicating purposes to the high frequency channels thus superposed upon the toll line. Where in 60 this type of system there are three or more stations associated with the toll line, each station is provided with means whereby it may call any of the other stations, preferably through the medium of a high frequency calling channel, and may establish conversational connection with the called station through the medium of any one of the other high frequency channels that is not at the time elsewhere in use. 65

70 One of the objects of the present invention is to organize a high frequency carrier system of this general type for the handling of toll or long distance calls between the stations in substantial accordance with present toll practice with respect to the putting up and taking down of connections, the operation of the calling, supervisory, guarding and disconnect signals, the selective signaling of any station by any other station, and 75 the common use of the high frequency channels of the system by the different stations and by different operators at the same station; and to provide a system where the reciprocal controls between the distant stations 80 necessary for the accomplishment of these results may be effected through the medium of the high frequency channels. To this end each of the high frequency channels in the preferred form of the invention is provided with a plurality of connection terminals at each toll station. These terminals at each station are accessible to a number of operators, and have associated with them signals that constantly inform the operators 85 of the condition of use or disuse of the channels, whether at the local or at a distant toll station, as well as a signal that informs an answering operator at each toll station of an incoming call over the particular channel with which the signal is associated. The operators at each toll station are provided with means whereby, upon taking an 90 idle channel for use, they may select and cause the operation of the calling signal associated with the channel at any desired one 95 of the distant stations, a busy indication at the same time being produced to guard the channel at other points. The channels are also adapted to co-operate with the connect- 100 105 110

2
ing apparatuses at the various associated toll stations in such a way that such signals as are necessary for the guidance of the operator in the supervision and disconnection of an established connection are controlled between the stations through the medium of the high frequency channels. Furthermore, the channels and the toll station terminal and channel extending apparatus 5 are arranged to co-operate in such a way that the selection of a channel and the selective calling of a particular station places the channel in operative relation with the called station and prevents its extension to 10 or use by any other of the distant stations. 15

Another object of the present invention is to provide means for automatically regulating the transmitted and received energy in the high frequency channel of a carrier 20 wave communicating system in such a way as to compensate for varying distance or normal energy attenuation between the particular transmitting and receiving stations and thus hold the transmission at a substantially 25 constant value. In the application of this feature to the embodiment of the invention herein disclosed means are provided for holding the low frequency current input from the carrier channel to the low frequency hybrid coil at an approximately constant value 30 irrespective of the degree of line attenuation between the particular two stations that are at the time connected over the channel. In a carrier communicating system where there 35 are but the two terminal stations to be interconnected, the line attenuation as affected by the distance between the stations is constant. In the present system, however, which contemplates a plurality of stations 40 on the toll line located at different points along the line, any two of which stations may be interconnected over any of the carrier channels that is free for use, the line attenuation is not constant, but varies with 45 the distance between the stations that are at the time in communication. The same carrier channel may be used for establishing connection with a station that is relatively close to the calling station, or with 50 a station that is relatively remote. Consequently the degree of amplification of the low frequency talking and signaling currents that is necessary for standard 55 transmission between any station and the most remote of the other stations on the line, may be greater than is desirable when connection is established with a less remote station and the line attenuation factor is correspondingly smaller. Such variation in 60 the volume of the transmitted and received energy is objectionable, not only because it leads to non-uniformity in the speech transmission but also because an unduly large low frequency input from the carrier channel 65 may cause sustained oscillations or

“singing” around the circuit as a result of unbalance in the low frequency hybrid coils. The present invention contemplates the provision of means for automatically regulating the transmission gains over the line to 70 an amount such that, irrespective of the distance between the communicating stations, substantially uniform transmission will be had and the setting up of persistent oscillations will be prevented. 75

The amount of energy delivered into the input of the low frequency hybrid of each station can be held approximately constant either by automatically varying in proportion to the separation of the stations the 80 amount of amplification to which the currents of the carrier channel are subjected, or by providing amplification in the proper amount for communication with the most distant station and automatically introducing 85 a variable compensating attenuation that holds the transmission gains down to the proper amount for communicating with a less distant station. In the embodiment of the invention herein disclosed, the latter 90 method is employed, and means are provided for automatically introducing artificial line sections of varying values into the transmitting and receiving branches of the chosen channel in the act of calling one 95 or another of the less remote stations. Normally, in this embodiment of the invention the artificial line sections are excluded from the branches; and when an operator establishes connection with the channel, her actuation of the controlling mechanism that acts to bring about the display of a calling signal of this channel at a particular desired one of the less remote stations, also automatically brings about the inclusion of 100 as many artificial line sections as are required to interpose the proper amount of attenuation. 105

The foregoing and other features are disclosed as co-operating in one and the same system in the present embodiment of the invention; but they are capable of separate use where it may be desirable for any reason to employ only part of the features that are presented herein. In addition, the system of the invention in the preferred form in which it is disclosed embodies other features that have not been particularly referred to in the foregoing general statement. The manner in which these other features, as 110 well as those that have been mentioned, are attained and realized will be explained in the following description; and the structures and combinations through which the objects of the invention are attained will be 115 more particularly defined in the appended claims. 120

The preferred embodiment of the invention is illustrated in the accompanying drawings, in which Figs. 1 to 5 inclusive, ar- 125 130 135

ranged as indicated in Fig. 6, show diagrammatically as much of the circuit organization at one toll station of the system as is necessary to enable the invention to be understood. It will be understood, without the necessity of diagrammatic representation, that there are a plurality of stations connected with the toll line L and that each of these stations may be in all respects identical in apparatus and circuit arrangement with the particular station illustrated in Figs. 1 to 5; the only differences between the stations being in the use of a harmonic producer at one of the stations and of a harmonic reproducer at each of the other stations, and in the particular calling channel modulating frequencies which each station is adapted to transmit and to which it is adapted to respond, as will be fully explained hereinafter.

Referring now to the preferred circuit organization as illustrated in Figs. 1 to 5 of the drawing, only as much of the wiring at a single one of the stations of the toll line is illustrated as is necessary to enable the invention to be understood; it being possible for one skilled in the art to which this invention pertains, by mere duplication and extension of the wiring and apparatus illustrated, and without the exercise of invention, to organize a system of such capacity as may be desired. As illustrated in the circuit diagram of Figs. 1 to 5, each one of the toll stations or toll points is connected with the toll line L through the medium of a two-way repeating coil or hybrid coil 100, this coil having one end of its line windings connected with the toll line and the other end connected with an artificial line or balancing network N that is constructed and arranged, as is well understood in the art, to balance and match in its characteristics the toll line with which connection is made. Extending from the bridge and series windings of this two-way repeating coil are two pairs of conductors, T and R, the pair T serving as the transmitting path to the toll line of the locally generated currents, and the pair R serving as the receiving path from the toll line of the currents generated at and transmitted from the other stations of the line. The transmitting and receiving paths each have connection with the local apparatus of the four communicating channels C¹, C², C³ and C⁴ and with the local apparatus of the calling channel C. At each of the toll stations there is also a connection of either the transmitting path T or the receiving path R with the base frequency channel BC. The connection of the transmitting path T is with the transmitting branches TC, TBC, TC¹, TC², TC³ and TC⁴ of the various channels respectively; and the connection of the receiving path R at each station is with the receiving branches RC, RBC, RC¹, RC²,

RC³ and RC⁴ of the various channels respectively. The transmitting branch apparatus of the base frequency channel BC is provided at only one of the toll stations. At the other three stations the transmitting branch apparatus of this channel is omitted and the apparatus indicated in connection with the receiving branch RBC is provided in its stead. At the station where the transmitting branch apparatus of the base frequency channel BC is provided, the circuit is closed at the points X and is opened at the points X'. At the other stations where the receiving branch apparatus of the base frequency channel is used, the circuits are closed at the points X' and are opened at the points X. The specific organization of the transmitting and receiving branches of the various channels will be described hereinafter. As a general description of the organization, it may be said that the transmitting branch TC of the calling channel C is so organized as to apply to the toll line the calling carrier frequency supplied through the amplifier HAC and modulated in accordance with one or another of three lower frequencies supplied by way of the associated modulating branches MB, MC and MD. These lower modulating frequencies are supplied from a harmonic producer HPL by distortion of the base frequency supplied by the oscillator O¹. Each of the modulating branches MB, MC and MD is made operative to apply its particular modulating frequency by the pressing of corresponding keys 51, 52 and 53. Each of the operators' positions OP, OP² etc. at the toll board is provided with a group of these keys. Each of the keys in being operated causes the application to the calling carrier frequency of the particular modulating frequency adapted to bring about the response of the receiving apparatus of the particular one of the distant toll stations that is being called. The groups of keys 51, 52, 53 at the different toll operators' positions operate to control their respective modulating branches through the medium of a group of common relays 3, 4 and 5, these relays in turn operating to energize the associated modulating branches through the medium of the relays 7, 8 and 9 respectively. Each group of station selecting keys 51, 52 and 53 has associated with it a pilot lamp 50, the illumination of which informs the operator that the calling channel and station selecting apparatus are in use either locally or at one of the other stations of the system.

The receiving branch RC of the calling channel is so organized that the detected calling carrier frequency received from the toll line brings about the operation of the relay 66, while the detected component of modulating frequency, if the frequency is that to which this particular station is

adapted to respond, brings about the operation of the relay 67. The relay 66 acts through the medium of the relay 2 to render ineffective all the station selecting keys 51, 52 and 53 in the various operators' position groups and to light the guard lamp 50 associated with each group of station selecting keys to inform the operator that the calling channel is elsewhere in use. The relay 67 acts through the medium of the relay 65 to co-operate with the relays 13, 11, 10 and 12 in controlling the illumination of the answering lamp 40 of the selected channel at the selected station to signal the incoming call to the called station operator.

The apparatus in the transmitting branch TBC of the base frequency channel BC includes the harmonic producer HPH and a base frequency oscillator OPH. The base frequency and its harmonics are conducted to a distributing circuit comprising the conductors 47, 48, from which the base frequency is separated out and applied to the transmitting path T by way of the branch 25 TBC, while the harmonics are selectively passed to the transmitting apparatus of the communicating channels C¹, C², C³ and C⁴ to supply the carrier frequencies for conveying the speech and signaling modulations over the respective channels.

The apparatus in the receiving branch RBC of the base frequency channel BC is so organized that the base frequency, received from the particular one of the four toll stations where the base frequency producing apparatus is located, is separated out from the other carrier frequencies passing over the receiving path R, is amplified, passed through a harmonic reproducer HRP, and the harmonics of the base frequency thus produced are supplied to the distributing conductors 47, 48, to supply the carrier frequencies required by the communicating channels C¹, C², C³ and C⁴ of the associated 45 station.

The organization of each of the communicating channels C¹, C², C³ and C⁴ is such that the voice currents received from the local telephone circuit by way of the talking conductors 79 and 80 are passed through the two-way repeating or hybrid coil 20, and caused to modulate the amplified carrier frequency received from the distributing conductors 47, 48 and the modulated carrier 55 frequency is conducted to the transmitting path T. The organization of each of the communicating channels is also such that the characteristic carrier frequency to which the channel is adapted to respond is 60 separated out from the other frequencies passing over the receiving path R, is demodulated, and the voice component is conveyed by way of the two-way repeating coil 20 to the local talking conductors 79 and 80, 65 while the carrier component is diverted and

caused to operate the relay 19. The relay 19 participates, through the medium of relay 11, in controlling the guarding and signaling operations incidental to the use of the associated channel.

Each of the communicating channels C¹, C², C³ and C⁴ has associated with it certain controlling and responsive elements, designated CC¹, CC², CC³ and CC⁴, respectively; and each of the channels is terminated, in 75 the present embodiment of the invention, upon spring jacks at a plurality of operators' positions of a toll switchboard. Each channel has a multiple jack MJ on each section of the toll board, and a single 80 answering jack AJ at a single one of the operators' positions. Each multiple jack has associated with it a busy lamp 41 to indicate the condition of busyness or idleness of the corresponding channel; and each 85 answering jack has an associated calling lamp 40, the illumination of which notifies the answering operator of an incoming call over that channel.

There may be as many toll sections and 90 operators' positions as traffic conditions render desirable. In the present instance, two operators' positions, OP and OP² are indicated. Each operator's position is provided with the usual equipment of connecting cord circuits and an operator's telephone set 39. Each of the connecting cord circuits, only two of which are shown in detail, may comprise a pair of connecting plugs 25, 26, with the conductors extending between them, together with a listening key 28, ringing keys 27 and 29, supervisory lamps 30 and 31 and supervisory relays 36 and 32. Each operator's position is also provided, as previously stated, with a group of station selecting keys 51, 52 and 53 and a calling channel guard or pilot lamp 50 with an associated relay 54 for preventing the lighting of the lamp under certain circumstances. A plurality of local lines, as 100 the line extending from station S and terminating upon the answering jack 58 and multiple jack 57, are brought into toll sections for interconnection with the carrier channels through the medium of the toll operator's connecting cord circuits. The terminal arrangement of the carrier channels is such that all of the channels are available for connection at each operator's position, so that each operator may be able to 105 utilize for interconnecting purposes as many of the channels as are not in use elsewhere in the system. The busy lamps 41 associated with each multiple jack channel extension terminal are controlled in such a way as to 110 indicate by their illumination the unavailability of the corresponding channel, whether it be due to the use of the channel at some position of the local board or at 115 some distant point on the toll line. The 120 125 130

particular sort of equipment shown for effecting interconnection between the channels and the local lines is merely illustrative, as, of course, such interconnection can be effected in any one of a variety of well known ways.

Specifically, the organization and operation of that part of the system which acts to generate, modulate, transmit, receive and 10 demodulate the high frequency carrier currents employed in the system is as follows: The frequency of the carrier waves selectively utilized by the communicating channels is determined, in the present embodiment of the invention, by a base or control frequency generated by a thermionic or vacuum tube oscillator OPH located at one of the toll stations or at some other point upon the toll line. This oscillator may be 15 of any suitable type but is preferably the usual and well-known audion type with a feed-back connection from its output into its input circuit. The frequency of the oscillatory current produced may be regulated 20 by an adjustable condenser, and may conveniently be, say, five thousand oscillations per second—although any other appropriate base frequency and its associated harmonic multiple frequencies may be employed. The 25 oscillator OPH supplies substantially sinusoidal oscillations to the input circuit of the harmonic producer HPH. An inductance 101 is bridged across this circuit. The magnitude of the oscillations supplied is such 30 as to overload the thermionic tube HPH; that is, to supply an input wave of greater amplitude than the tube can repeat without distortion. The repeated oscillations in the 35 output circuit of the tube HPH are therefore of non-sinusoidal wave form, which is the equivalent of a base frequency current of sinusoidal form and a series of currents of frequencies which are multiples or harmonics of the base frequency. The plate 40 current source, P, of the overloaded tube or harmonic producer HPH is connected by a circuit comprising a resistance 102 and an inductance 103 which constitutes an impedance that is of the order or magnitude of the 45 impedance between the plate and filament of the tube or greater. This impedance relationship assists in producing distortion and in stabilizing the output circuit. The output 50 circuit of the harmonic producer HPH is connected with a distributing circuit 47, 48, by means of a transformer 104, and the distributing circuit is thus supplied with both the base and the harmonic frequency 55 oscillations. From the distributing circuit 47, 48 the base and harmonic frequencies are selected by means of tuned circuits leading to the transmitting branches of the calling and various communicating channels and the transmitting branch of the base 60 frequency channel. The inductance of the 65

transformer 105 of the base frequency transmitting branch and the capacities of the fixed and variable condensers associated with it are so adjusted that only the base frequency oscillations are selected. Similarly 70 the constants of the transformers and condensers of the other tuned circuits leading from the distributing circuit are so adjusted that each of these tuned circuits selects a different one of the harmonics of the 75 base frequency. The harmonic frequencies selected by the transmitting branches of the communicating channels C¹, C², C³ and C⁴ may be ten thousand, fifteen thousand, twenty thousand, and twenty-five thousand cycles respectively, and the harmonic frequency selected by the transmitting branch of the calling channel C may be 30,000 cycles.

The base frequency oscillation selected 80 from the distributing circuit by the tuned circuit including the transformer 105 passes through a potentiometer 106, from which it is supplied at the desired potential to the input circuit of the amplifier HA. The output circuit of the amplifier HA is inductively coupled with the terminals of a band filter HF through which the amplified base frequency oscillation passes to the transmitting path T. The band filter HF 85 is of the well-known type described in Patent No. 1,227,113 to Campbell, patented May 22, 1917. The characteristics of this filter, which consists of recurrent similar sections having series and shunt capacities and inductances, is such that it transmits 90 oscillations of the base frequency with little attenuation and effectively diverts from this branch currents of frequencies differing more than a slight amount from the 95 base frequency.

As has been stated, the base frequency oscillator is provided at but one station or point on the toll line. At the other toll stations or points the base or controlling frequency thus supplied to the line passes from the line thru the two-way repeating coil 100 of the station into the receiving path R. The receiving branch RBC of the base frequency channel is provided with a transformer 107 with associated condensers and inductances to constitute a tuned circuit that acts to divert the base frequency oscillation from the receiving path to the amplifier HRA¹ by way of the potentiometer 108, 110 while permitting the free passage of the other carrier frequencies through the receiving path to their respective channels. The base frequency thus selected is amplified by the amplifier HRA¹, and the amplified oscillations are impressed upon the input circuit of the thermionic tube HRP. The magnitude of the oscillations are such as to overload this tube, with the result that, as in the case of the tube HPH associated 115 with the base frequency oscillator OPH, 120

the repeated oscillations are distorted into a series of currents the frequencies of which are the harmonics of the base frequency current, the tube HRP thus acting as a harmonic regenerator. The base frequency and its harmonics are then amplified by the amplifier HRA² and are impressed upon the distributing circuit 47, 48 through the transformer 109. From the distributing circuit 10 the harmonic frequencies of the base or controlling oscillation are selectively supplied to the transmitting branches of the channels C¹, C², C³ and C⁴ by way of the tuned circuits previously referred to. Thus at the 15 toll station where the base frequency oscillator OPH and the harmonic producer HPH are located the communicating channel carrier frequencies are supplied directly, while at the other stations they are supplied by a 20 harmonic regenerator HRP controlled by the base frequency oscillations received over the toll line. Consequently the corresponding carrier frequency oscillations are identical in frequency at all of the stations of 25 the toll line.

The organization illustrated and described for producing a plurality of harmonic carrier frequencies from a base frequency by distorting that frequency, and 30 for insuring identical frequencies of the carrier oscillations employed at each of the various toll stations by controlling the carrier frequencies at all points from a single base frequency is substantially in accordance 35 with the organization disclosed in the British Patent No. 131,426. The method and organization described above for synchronizing corresponding carrier waves at all stations is the preferred way of securing 40 this result for use in connection with the present embodiment of the invention. But it will be understood that other ways of securing substantially identical frequencies of the carrier waves at the different points at 45 which they are applied may be used.

At each of the communicating channels C¹, C², C³ and C⁴ the particular carrier frequency diverted from the distributing circuit 47, 48 by means of the corresponding 50 tuned circuit is applied to the terminals of a potentiometer 110 from which the carrier oscillations at the desired potential are applied to the input circuit of an amplifier HAC¹. The output circuit of the amplifier 55 is connected by way of the potentiometer 111 with the input circuit of a modulator MC¹. The input circuit of the modulator MC¹ also has connection by way of the inductive coupling 112 and the potentiometer 60 113 with the appropriate winding of the low frequency hybrid coil 20 that links the carrier channel with the low frequency or talking circuit. The talking conductors 79 and 80 extending to the spring jack terminals of this communicating channel are con-

nected through condensers with the line side of the hybrid coil or two-way repeater, and the other side of the repeater is connected through condensers with a balancing network N, the characteristics of which are 70 made to match the characteristics of the low frequency lines adapted to be connected with the channel. The voice currents that reach the repeater 20 by way of the conductors 79 and 80 are consequently repeated 75 and impressed at the proper potential upon the input circuit of the modulator MC¹ and are there combined with the carrier frequency derived from the distributing circuit 47, 48 to cause correspondingly modulated 80 carrier current to flow in the output circuit of the modulator. The output circuit of the modulator is connected through an inductive coupling 114 with two sections of artificial line, one of which is controlled by the 85 relay 26 and the other by the relay 27. The series windings of each section are normally short-circuited in resting contacts of the relays 26 and 27 and the shunt windings, 90 each of which is bridged across the circuit 95 between midpoints of the series windings, are normally open at front contacts of the relays 26 and 27. Consequently in the de-energized condition of relays 26 and 27, the artificial line sections are excluded from the 100 circuits of the transmitting branch. The second artificial line section is connected with a band filter of the type disclosed in the Campbell patent previously referred to. The characteristics of this particular form 105 of the Campbell band filter are such that it suppresses any currents of the frequency of the voice currents in the talking conductors of the channel which might be repeated as low frequency currents by the modulator. 110 The band filter MFC¹ of each of the channels serves to transmit currents of a range of frequencies including the carrier frequency of that channel and frequencies extending up and down from the carrier frequency by an amount depending upon the highest frequency current that it is desired 115 to transmit from the low frequency or talking circuit.

The band filters MFC¹ of the four communicating channels, the band filter HF of the base frequency channel BC, and the band filter MFC of the calling frequency channel C are all arranged with their terminal shunts connected in series in the transmitting path 43, 44; and the constants of these various filters are so adjusted that each filter passes freely to the transmitting path the carrier frequency from its own channel while at the same time preventing the frequencies supplied through the filters of the other channels from being diverted into its channel. The band filters DFC¹ of the receiving branches of the various communicating channels C¹, C², C³ and C⁴, the tuned 120

circuit of the receiving branch RBC of the base frequency channel BC, and the band filter DFC of the receiving branch RC of the calling channel C, are similarly connected to 5 the receiving path R extending from the high frequency hybrid coil 100; and the constants of the filters and the tuned circuit are so adjusted that each diverts from the receiving path R into its own channel the 10 particular frequency to which the channel apparatus is adapted to be responsive, while permitting to pass freely through the series circuit the frequencies which the other channels are adjusted to divert.

15 The receiving branch of each of the communicating channels is provided with a band filter DFC¹ adjusted, as stated above, to divert into the channel the characteristic frequency band of that channel. After passing through the band filter, the diverted oscillatory current passes through conductors controlled at back contacts of two relays 36 and 37 each of which is adapted when operated to include in the receiving branch an 20 associated section of artificial line, the arrangement and control of these artificial line sections being the same as that previously referred to in the description of the artificial line sections included in the transmitting 25 branch of the circuit. The oscillatory current diverted through the band filter DFC¹ is then carried through a potentiometer 115 and applied at the proper potential to the low side of a shielded transformer 116, the 30 high side of which is included in the input circuit of the detector DC¹. The C potential for the grid of this detector tube is derived from the filament battery by including a resistance 117 in the filament current 35 supply circuit beyond the point where the input circuit of the detector is connected with the filament circuit. The output circuit of the detector DC¹ is connected to the input circuit of the amplifier AC¹ through 40 the medium of a transformer 118 which is designed to transmit efficiently the voice frequencies obtained from the demodulation of the modulated carrier wave; as well as the unmodulated carrier component. The output 45 circuit of the amplifier AC¹ is connected to the low pass filter LPC¹, designed to pass the voice frequencies and exclude the carrier frequencies, by way of a transformer 119. The other terminals of the low pass 50 filter are connected to the bridge terminals of the two-way repeating coil 20, where the voice currents are divided between the talking conductors 79 and 80 and the balancing network N in such a way as to have their 55 effects as nearly as possible neutralized in the coil of the repeater that is connected with the outgoing transmission branch of the channel. The output circuit of the amplifier AC¹ also has a branch path through a 60 high pass filter HPC¹ which acts to pass the

carrier wave component and to prevent the passage of the demodulated voice frequency component. The other terminals of the high pass filter HPC¹ are connected with the low side of a transformer 120, the high side 70 of which is connected in the input circuit of the rectifier tube HRC¹. The output of the rectifier is connected with the winding of a relay 19 which is adjusted to respond and hold its contacts closed as long as the associated communicating channel is receiving the carrier frequency components which it is adapted to divert from the receiving path R.

75 The filament and plate energizing currents are supplied to the apparatus of the transmitting branch of the channel under the control of a relay 24. The supply circuits are so arranged that the filament and plate current is normally disconnected and is applied to the transmitting branch apparatus only 80 when the relay 24 is energized.

85 As has previously been stated, the transmitting path T of each toll station is arranged to receive a calling carrier frequency by way of the transmitting branch TC of 90 the calling channel C, the calling carrier being modulated by lower frequencies in accordance with which of the modulating branches MB, MC and MD is made operative. In accordance with the present embodiment of the invention, the calling carrier frequency is derived from the harmonic distributing circuit 47, 48 through a tuned circuit and is applied through a potentiometer 95 at the proper potential to the input circuit of the amplifier HAC the output circuit of which is connected by way of potentiometer 68 with the input circuit of the modulator MCC. The calling carrier may 100 be of any suitable frequency that differs selectively from the frequencies that are used by the base channel BC and the four communicating channels C¹, C², C³ and C⁴, but as stated, is assumed in the present description to be 30,000 cycles.

105 The modulation of the calling carrier wave is effected by lower frequency currents produced by the oscillator O¹ and the harmonic producer HPL. The oscillator O¹ is of the well-known type having a feed-back connection from its output circuit to its input circuit by way of the inductive coupling 115 111. The output circuit of the oscillator O¹ is connected with the input circuit of the harmonic producer tube HPL. The magnitude of the oscillations supplied is such as to overload the tube HPL, thus causing the tube to distort the sinusoidal wave of the oscillator O¹ and produce in its output circuit 120 non-sinusoidal currents that are the equivalent of the base frequency current of the oscillator together with the harmonics of the base frequency. This series of currents is supplied by way of transformer 122 to the 125 distributing conductors 93, 94. The various 130

5 frequencies that are thus supplied to the distributing circuit are selectively diverted by way of a plurality of tuned circuits, including the transformers 95, 96 and 97 and their 10 associated variable condensers, to the potentiometers 123, 124 and 125 respectively of the modulating circuits MB, MC and MD. From the potentiometers the oscillations of the selected frequencies are conducted to the 15 input circuits of the amplifiers A¹, A² and A³. The output circuits of these amplifiers are connected in tuned branches of the circuit M leading to the modulator MCC, the tuning of the branches being such as to 20 permit the passage to this circuit of the frequency of the corresponding modulating current branch and to exclude from the branch in question the frequencies of the other modulating current branches that feed 25 into the circuit M. The circuit M is connected to modulator MCC via transformer 126.

30 The modulating current branches MB, MC and MD are normally inoperative and are made operative under the control of the 35 associated relays 7, 8 and 9 respectively, these relays acting when operated to apply current from the filament and plate batteries F and P to energize the apparatus of the corresponding branches. The oscillator O¹ with its associated harmonic producer HPL, and the amplifier HAC and modulator MCC of the transmitting branch of the calling channel are also normally inert. When any 40 one of the relays 7, 8 and 9 is operated to energize the apparatus of the corresponding modulating branch, it also acts through the medium of the relays 69 and 78 to energize the above mentioned oscillator O¹, harmonic producer HPL, amplifier HAC and modulator MCC to render operative the devices that furnish the calling carrier wave and its modulating frequency.

45 The oscillator O¹ may be arranged to produce oscillations of any suitable frequency as, for instance, 200 cycles. As a result of the action of the harmonic producer HPL there is transmitted to the distributing circuit 93, 94 the base frequency 200 of the 50 modulator O¹ together with the harmonic frequencies thereof. If three modulating current paths MB, MC and MD are employed, these paths have their constants adjusted to divert from the distributing circuit, amplify and pass to the circuit M the three harmonic frequencies 400, 600 and 800. If additional modulating current branches 55 are to be used, they may be adjusted to employ the base frequency 200 and other higher 60 harmonic frequencies.

65 As will subsequently be explained, each of the toll stations is adapted to have the receiving branch of its calling channel selectively responsive to a particular one of these 70 lower modulating frequencies; so that the

transmitting branch of the calling channel at each station is arranged to transmit the calling carrier frequency and as many lower frequency modulations thereof as there are 75 distant toll stations to be selectively controlled or signaled. The transmitting branch of the calling channel at each toll station is of course arranged to modulate the calling channel frequency only with the lower frequencies to which the distant toll 80 stations are responsive, and not with the lower frequency to which the particular toll station itself is responsive. Thus the particular station illustrated in the drawing is assumed to be responsive to the 200 modulating frequency, and consequently the modulating current branches are so arranged as not to apply the 200 frequency to the path M, but to apply the three harmonic frequencies 85 400, 600 and 800. At the toll station responsive to the 400 frequency the modulating current branches are arranged to employ the 200, 600 and 800 frequencies; and similarly at the other stations the particular 90 modulating frequency to which that station is adapted to respond is not arranged to be applied to the transmitting branch.

95 At each of the toll stations there is a connection from the receiving path R by way of a band filter DFC and a shielded transformer 127 to the input circuit of a detector DC. The band filter DFC is designed to divert into the receiving branch of the calling channel C the band of frequencies including the calling channel frequency, in this instance assumed to be thirty thousand, and its modulations extending up and down from this frequency through a range determined by the modulating frequencies derived from the path M. The 100 output circuit of the detector DC is connected through a transformer 128 with the input circuit of an amplifier AC. The output circuit of the amplifier is connected 105 through the high pass filter HPC and the transformer 129 with the input circuit of the rectifier tube HRC. The output circuit of the rectifier tube includes the winding of the relay 66, which is thus adapted to respond to the presence in the circuit of the 110 unmodulated component of the calling channel carrier wave. The output circuit of the amplifier AC also has connection through the medium of the transformer 130 with a low pass filter LPC. This filter is designed 115 to pass to the input circuit of the rectifying tube LRC, through the medium of the transformer 131, the particular modulating frequency of the calling carrier wave to which this toll station is responsive, and to exclude 120 the other modulating frequencies to which the other toll stations respond, the demodulation of the modulated calling carrier wave into its carrier and modulating components 125 being effected in the detector DC. The out- 130

- put circuit of the rectifying tube LRC is connected with the winding of the relay 67, which relay therefore is operated only when the calling carrier wave is modulated with the particular frequency to which the associated station is adapted to respond. At each of the other stations there will be substituted for the low-pass filter LPC a band filter designed to pass the particular modulating frequency to which that station is intended to respond and to exclude other frequencies. Thus, for example, the station which is intended to be called by means of the frequency sent out through the channel A², namely 600 cycles, will be designed to pass 600 cycle current freely and exclude currents of 400 and 800 cycles or any other currents of frequencies differing materially from 600 cycles.
- In outline, the operation of the system is as follows: When any of the toll board operators has occasion to establish a connection over the toll line, she picks up the toll plug of one of her connecting cord circuits and inserts it into a multiple spring jack of a channel the idle condition of which is indicated by the unilluminated condition of the associated busy or guard lamp. The insertion of the plug causes the lighting of all of the guard lamps associated with the multiple spring jacks of this channel on the other toll board sections of the calling station; and also, by causing the energization of the channel apparatus and the application to the toll line of the corresponding carrier wave, brings about the lighting of the guard lamps associated with the multiple spring jacks of this channel upon the switchboards of all the distant toll stations of the system.
- At the same time the control over the establishment of connection with the selected channel at the distant stations is transferred from the operators at those stations to the operator at the calling station. As a result, the operators at the distant stations are prevented from gaining access to the selected channel, if they should attempt to do so in disregard of the lighted busy lamp; but the calling operator has the power to bring about the extension of the channel to the spring jacks at the particular distant station that she may select.
- In selecting the station to which the call is to be extended, the calling operator first notes the condition of the pilot lamp associated with her group of station selecting keys, and if the lamp is dark, indicating that the calling channel is not in use, she presses the key corresponding to the station desired, and at the same time presses the ringing key associated with the toll end of the connecting cord circuit she is using. The depression of the station selecting key energizes the calling channel to apply the carrier frequency of that channel modulated with the particular lower frequency to which the selective apparatus of the desired station is adapted to respond. The energization of the calling channel deprives all of the distant toll station operators of control over the calling channel and also lights the calling channel pilot lamps associated with the station selecting keys of these operators' positions. At the same time, the other toll switchboard operators of the station that is calling have their calling channel pilot lamps lighted and are deprived of control over the calling channel.
- The lighting of the calling lamp associated with the selected channel at each station depends upon the concurrent energization of the communicating channel, the application of ringing current to the channel, and the application to the calling channel carrier wave of the particular lower modulating frequency to which that station is responsive. The apparatus responsive to the energization of the communicating channel and to the application of ringing current operates at all of the distant toll stations; but the apparatus responsive to the particular modulating wave applied to the calling carrier wave operates only at the station that is being called, and consequently the calling lamp at that station is the only one to respond when the calling operator simultaneously presses her station selecting key and her cord circuit ringing key. The response at the called station which brings about the lighting of the calling lamp also extends the corresponding communicating channel to the spring jacks of the associated toll switchboard; so that the called station operator in inserting the toll plug of a pair of connecting cords into the answering spring jack is thereupon in communication with the calling operator over the selected channel,—the transmitting branch of the channel at the called station being energized by the insertion of the plug. In pressing the station selecting key to signal the desired station, and simultaneously pressing the cord circuit ringing key, the calling station operator also brings about the automatic adjustment of the communicating channel energy to the distance between stations by the inclusion in the channel transmitting and receiving branches of such artificial line sections as are necessary to introduce the required compensating attenuation, thus holding the volume of transmission substantially constant and preventing "singing".
- While the connection between the calling and called stations is established, the operators may signal each other and each control a supervisory lamp in the cord circuit of the other by pressing their respective ringing keys. The pressing of the ringing key applies a special ringing control modulating frequency to the carrier current at

the associated end of the channel. As a result, apparatus responsive to this frequency at the other end of the channel operates and applies ordinary ringing current to the 5 channel extension leading to the spring jacks in one of which the connecting circuit plug is inserted. This causes the lighting of the associated connecting circuit supervisory lamp. In the application of the ringing 10 control modulating frequency at one end of the channel, and the resultant application of ordinary ringing current at the other end of the channel, provision is made for automatically disconnecting from the channel 15 extension circuits at both ends normally connected responsive apparatus that might otherwise be accidentally operated; and also for short circuiting the output winding of the low frequency hybrid coil to prevent the 20 unbalance caused by the application of ringing current from causing a coupling of the channel receiving and transmitting branches in such a way as to set up sustained oscillations. When the conversation is completed, 25 the operators at the calling and called stations, respectively, disconnect by withdrawing the plugs of their connecting cord circuits from the channel extension spring jacks in which they have been inserted; and 30 when disconnection has taken place at both ends of the channel, the busy or guard lamps associated with the channel spring jacks at all points in the system are extinguished, and the channel is again available for use. 35 The calling channel is released for use by other operators, and the pilot lamps associated with the station selecting keys at all other operators' position of the system are extinguished, as soon as the calling operator 40 has released her station selecting key.

The operation of the system will now be described in detail. When one of the local subscribers, as the subscriber at station S, wishes to communicate with a subscriber at 45 another one of the toll stations associated with the carrier toll line, he takes his telephone receiver from its hook, thus operating the associated line relay 56 and lighting the answering lamp 59 associated with the 50 answering spring jack 58 before the operator at position OP. The operator in responding inserts plug 26 of one of her pairs of cords into spring jack 58, thus operating the cut-off relay 55 and releasing line relay 56 to 55 extinguish answering lamp 59, in the usual way. The insertion of plug 26 into spring 60 way. The insertion of plug 26 into spring jack 58 also closes the energizing circuit of supervisory lamp 31, which, however, remains dark as a result of the closure of a shunt around it due to the operation of supervisory relay 32. The operator then 65 communicates with the calling subscriber by throwing her listening key 28, thus bringing her telephone set 39 into connection with the talking strands of the cord circuit.

Upon learning from the calling subscriber that he desires a connection that must be completed over the toll line, the operator observes the condition of busyness or idle- 70 ness of the various channels of the carrier toll line, as indicated by the illuminated or unilluminated condition of the busy lamps 41 of the various channels, and inserts the plug 25 of the cord circuit into a channel multiple spring jack the associated busy 75 lamp of which is dark. Assuming that this is the multiple spring jack MJ¹, the insertion of plug 25 completes a circuit that extends from battery through resistance 98, registering sleeve contacts of plug 25 and 80 spring jack MJ¹, conductor 81 and winding of relay 12 (Fig. 2) to ground. Relay 12 in operating closes a circuit that extends from battery in parallel thru the busy lamps 41 associated with the multiple spring jack 85 terminals of the corresponding channel at all the operators' positions of this toll station, conductor 82 and inner right hand front contact and armature of relay 12 to ground. Thus all of the local busy lamps of 90 this channel are lighted to indicate the busy condition of the channel immediately upon its being taken for use. Relay 12 in operating also closes a circuit that extends from battery through the winding of relay 10, inner right hand armature and back contact of relay 11, and left-hand front contact and armature of relay 12 to ground. Relay 10 thereupon operates and closes a locking path 95 to maintain its energization by way of lower armature and front contact of relay 10 and outer right hand armature and back contact of relay 11 to ground by way of left hand front contact and armature of relay 12. The operation of relay 10 extends the talk- 100 ing conductors of channel C¹ through to the conductors 79 and 80 that are branched to the multiple jacks of this channel at the various operators' positions, and thus ex- 105 tends the talking circuit of the operator's connecting cord pair through to this par- 110 ticular channel.

When relay 12 operates, as has been de- 115 scribed, in response to the insertion of plug 25 into multiple jack MJ¹, it brings about the energization of the corresponding channel C¹. This is accomplished by the closure of a circuit that extends from battery through the winding of relay 24 (Fig. 5), conductor 89 and outer right hand front contact and armature of relay 12 to ground. When relay 24 operates it connects the filament and plate batteries with amplifier HAC¹ and modulator MC¹ of channel C¹. 120 As has been described, the amplifier HAC¹ of channel C¹ is connected with the high frequency harmonic distributing conductors 47, 48 by way of a tuned circuit that is adapted to pass the 10,000 frequency to the 125 amplifier HAC¹. Consequently when relay 1¹

- 24 connects the filament and plate batteries with the amplifier HAC¹ and modulator MC¹, the 10,000 frequency is applied by way of channel C¹ to the carrier toll line.
- 5 At each of the other toll stations, the 10,000 frequency thus applied to the toll line is transmitted by way of the two-way repeating coil 100 of each of the toll stations to the associated receiving path R; and,
- 10 passing over the conductors 45, 46 of the receiving path, is diverted into the receiving branch RC¹ of the corresponding channel C¹ at each of the distant toll stations of the line. At each of the distant toll stations, the
- 15 10,000 frequency is diverted from the receiving path R by way of the band filter DFC¹ of the receiving branch RC¹, thence by way of normally closed contacts of relays 37 and 36, potentiometer 115, shielded transformer 20 116, detector DC¹, inductive coupling 118, amplifier AC¹, high pass filter HPC¹, inductive coupling 120, and rectifier tube HRC¹, where the amplified high frequency wave is rectified and brings about the response of relay 19. Relay 19 in operating closes a circuit that extends from battery through the winding of relay 11 (Fig. 2), conductor 90 and front contact and armature of relay 19 to ground. Relay 11 in operating closes a circuit that extends from battery through all of the busy lamps 41 associated with the multiple jack terminals MJ¹ of this particular channel at the various toll board positions, thence by way of 35 conductor 82 and left hand front contact and armature of relay 11 to ground. Thus the taking of channel C¹ for use at the calling station and the consequent application of the 10,000 carrier frequency causes the 40 lighting of the busy or guard lamps associated with all the channel extensions not only at the local toll station but also at all of the distant toll stations, and guards the channel against being employed by other 45 operators.
- Having appropriated an available channel, the operator now proceeds to select and signal the particular one desired of the toll stations having access to the channel,—first noting, however, the condition of the pilot lamp 50 to ascertain whether or not the calling channel is elsewhere in use. If the pilot lamp 50 is unilluminated, thus indicating that the calling channel is free, the 55 operator presses the ringing key 27 associated with the cord circuit that is being used, and at the same time presses a particular one of the group of station selecting keys 51, 52, 53. Assuming that it is key 53 that corresponds to the toll station wanted, the pressing of this key closes a circuit that extends from battery through the winding of relay 2 (Fig. 2), winding of relay 5, conductor 71, left hand contact and switch spring of key 53, conductor 76, and back
- contact and armature of relay 2 to ground. Consequently relay 2 and relay 5 are both energized. Relay 5 in operating closes an alternative energizing circuit for itself and relay 2 that extends by way of the lower front contact and armature of relay 5, conductor 70, right hand contact and switch spring of key 53, and winding of relay 54 to ground. The instant relay 2 operates, it opens at its back contact the previously traced initial energizing circuit for itself and relay 5; but these relays are held operated over the second traced circuit by way of the lower contact and armature of relay 5. As the operating ground that gives the station selecting group of keys 51, 52 and 53 of each operator's position control over the common relays 3, 4 and 5 is disconnected from the common conductor 76 the instant the common relay 2 operates, keys 51, 52 and 53 of the other operators' positions are ineffective as long as any one of the operators has one of her keys 51, 52 and 53 depressed. The calling operation is further guarded from interference the instant the common relay 2 operates by the closure of a circuit that extends from battery by way of parallel branches at the various operators' positions each including the pilot lamp 50 and back contact and armature of relay 54 and thence by way of the common conductor 77 and front contact and armature of relay 2 to ground. The closure of this circuit causes the lighting of the calling channel pilot lamp 50 at each of the other positions to indicate that the calling channel is in use. It is unnecessary that the pilot lamp 50 be lighted at the position of the operator who is making the call; and the prevention of the lighting is accomplished as a result of the inclusion of the winding of relay 54 of the calling operator's position in the circuit previously described as being closed at the lower front contact and armature of relay 5 upon the operation of that relay. Relay 54 in operating opens the branch from conductor 77 through the pilot lamp 50 of the calling operator's position, and consequently the pilot lamp at this position remains dark.
- As has been stated, when the calling operator presses the key 53 of the station selecting group, the common relay 5 is operated. Relay 5 in operating closes a circuit that extends from battery through the winding of relay 9 (Fig. 1), conductor 35 and upper armature and front contact of relay 5 to ground. Relay 9 in operating closes a circuit that extends from battery in parallel branches through the windings of relays 69 and 78, and thence to ground by way of the upper armature and front contact of relay 9. The energization of relay 69 connects the plate and filament batteries P and F with the oscillator O¹ and

the harmonic producer HPL that produce the base frequency and harmonic frequencies used to modulate the calling channel carrier wave for station selecting purposes.

5 The energization of relay 78 connects the plate and filament batteries with the harmonic amplifier HAC and the modulator MCC, that amplify the calling harmonic frequency derived by way of the tuned 79 branch circuit 63, 64 from the harmonic distributing circuit 47, 48 and apply this calling frequency modulated by a particular one of the lower or station selecting frequencies to the toll line. When relay 9 10 operates it also, at its lower armatures and front contacts, connects the plate and filament batteries with the amplifier A³ of the 800 cycle branch of the circuit M. Consequently the result of the operation of relay 9 in response to the depression of operator's station selecting key 53 and the energization of the common relay 5, is to set 85 in operation the lower or station selecting frequency oscillator O¹ and harmonic producer HPL, to select and amplify the 800 90 cycle harmonic, and apply to the toll line the 30,000 or calling frequency harmonic modulated with the 800 cycle station selecting frequency.

30 At each of the other toll stations, the 30,000 calling frequency modulated with the 800 station selecting frequency passes into the receiving branch R of the two-way repeater 100 of that station, and is diverted 95 into the receiving branch RC of the calling channel as a result of the selective action for this particular frequency of the band filter DFC. The high frequency component of the modulated 30,000 frequency wave, 100 after passing through the detector DC, the amplifier AC, and the high pass filter HPC, is rectified in the rectifier tube HRC and operates the relay 66. The low frequency component of the calling wave, after being 105 detected and amplified in the detector DC and amplifier AC, passes through the low pass filter LPC to the rectifier tube LRC where it is converted into unidirectional current for the operation of relay 67. As has 110 been described, the characteristics of the low pass filters LPC at the various stations are so adjusted that each station is selective with respect to a particular one of the low frequency or station selecting components 115 of the calling wave. As a result, when the calling wave of 30,000 frequency is applied to the toll line, all of the relays 66 at the distant toll stations are operated, but the relay 67 is operated only at the particular 120 station that has its low pass filter LPC adjusted to the particular station selecting frequency with which the calling wave is modulated. Relay 66 in operating closes a circuit that extends from battery through the winding of relay 2 (Fig. 2), resistance 125 65

6, conductor 36 and front contact and armature of relay 66 to ground. The closure of this circuit operates relay 2 to make ineffective the initial energizing circuit over which the keys 51, 52 and 53 at all the 79 associated operators' positions have control over the calling and station selecting operations; and also to illuminate the pilot lamps 50 associated with these keys, in the manner already described. Thus the application of 75 the calling frequency by any of the operators' signals all of the other operators at all of the toll stations of the system that the calling frequency is in use, and also positively prevents any other than the calling 80 operator from initiating a call.

When the relay 67 operates at the particular toll station that is being called, it closes an energizing circuit for the associated relay 65; and that relay in operating applies 85 ground to the associated conductors 38, thus rendering these conductors effective to operate with other signal controlling apparatus in a manner that will subsequently 90 be described.

The application of this station selecting frequency that has brought about the operation of relay 65 at the called toll station has been accompanied, as already stated, by the pressing of the ringing key 27 in the 95 calling operator's connecting cord circuit. The pressing of ringing key 27 applies current from ringing generator 99 to the talking conductors 79 and 80 of the channel in to the multiple jack MJ¹ of which the plug 100 25 is inserted. This ringing current passes from the conductors 79 and 80 by way of the upper armatures and front contacts of relay 10, upper armatures and back contacts of relay 13, and left hand back contact 105 and armature of relay 14 to the winding of relay 15, thus causing the energization of that relay. The energizing circuit of the slow-releasing relay 17 is normally closed 110 by way of the back contact and armature of relay 15, so that when relay 15 is operated by the operator's application of ringing current to the conductors 79 and 80, the energizing circuit of relay 17 is interrupted and the relay releases its armature. This closes a circuit that extends from battery in parallel branches through the windings of relays 21 and 23 and back contact 115 and switch spring of relay 17 to ground. Relay 23 in operating takes part in the performance of the attenuation controlling function in a manner that will be described hereinafter. Relay 21 in operating closes a circuit that extends from battery through the winding of relay 42 (Fig. 1), conductor 60 and upper front contact and armature of relay 21 to ground. Relay 42 in operating applies current from the plate and filament batteries to the circuits of the ringing frequency oscillator and amplifier GO 120 130

and GA, thus energizing these elements and causing them to generate and amplify a ringing frequency wave that may conveniently have a frequency of 133 cycles per second. At the same time relay 21 in operating breaks the talking conductors 84, 85 of the transmitting branch of channel C¹ from its normal connection with the series winding of the two-way repeater 20, and 10 connects them with the conductors 61 and 62 extending to the ringing frequency oscillator. The result, therefore, is to apply the ringing frequency to the modulator MC¹ of channel C¹ and effect a corresponding 15 modulation of the carrier wave that this channel is applying to the toll line. At each of the distant toll stations this ringing frequency component is detected and amplified in the receiving branch RC¹ of 20 channel C¹; and after passing through the low pass filter LPC¹, causes the operation of the relay 18, which is bridged across the receiving branch conductors 91, 92 in a circuit tuned to the 133 cycle ringing frequency. The energizing circuit of slow-releasing relay 16 is normally closed at the 25 back contact and armature of relay 18. When relay 18 is energized as a result of the application of the ringing frequency at 30 the calling station, the energizing circuit of relay 16 is broken and relay 16 releases its armature and closes its back contact. This completes a circuit that extends from battery through the winding of relay 13, 35 armature and back contact of relay 16 and armature and switch spring of relay 17 to ground, relay 17, as has been described, being normally held energized by the closure of its circuit at the back contact of 40 relay 15.

Relay 13 in operating applies ringing current from generator 119 to the talking conductors 79, 80 of the corresponding channel extending to the spring jacks of the associated toll board sections. However, at this 45 time this application of ringing current is without effect, as this particular channel is idle and none of the spring jacks associated with conductors 79 and 80 have plugs inserted in them. Relay 13 in operating also 50 closes a circuit that extends from battery through the winding of relay 14 and inner lower front contact and armature of relay 13 to ground. The particular function performed as a result of the operation of relay 14 will be described hereinafter. At 55 its outer lower front contact and armature, relay 13 in operating closes one break in a conductor that is normally also broken 60 at one of the front contacts and armatures of relay 65, and also at a front contact and armature of relay 11, and which conductor includes the winding of relay 10. Consequently, in order to effect the energization 65 of relay 10 as a result of the operation of relay 13, the relays 65 and 11 must also simultaneously be operated. It will be remembered that the relays 11 at all of the distant toll stations are operated through the medium of their associated relays 19 70 at the instant the carrier frequency of the corresponding channel is applied as a result of the calling operator taking that channel for use. In like manner, as has just been described, the relays 13 at all 75 of the distant stations are operated by the application of the ringing modulating frequency to the carrier when the calling operator presses the ringing key 27. Therefore, two of the three normal breaks in 80 the energizing circuit of relay 10, namely, those associated with the relays 11 and 13 respectively, are closed at this moment at all of the distant stations. But the third break in this energizing circuit, namely, 85 that at a front contact and armature of relay 65, is closed only at the station whose relay 65 is adapted to be selected by the application of the 800 cycle station selecting frequency determined by the pressing 90 of the operator's station selecting key 53 that was assumed to have been chosen. Consequently the operating combination necessary for the energization of the relay 10 is effected only at the station determined 95 by the pressing of the particular selecting key 53.

When the relay 10 operates, it closes a locking circuit for itself by way of its lower armature and front contact and the 100 outer right hand armature and front contact of relay 11 to ground. Relay 10 in operating also closes a circuit that extends from battery through the calling lamp 40 (Fig. 3) associated with the answering jack 105 AJ¹ that serves as the answering extension of this channel, conductor 83, inner upper armature and front contact of relay 10, armature and back contact of relay 49, and left hand back contact and armature of relay 12 to ground. This lights the lamp 40, and indicates to the answering operator of 110 channel C¹ at the selected toll station that she is being called over that channel. At the same time relay 10 has closed the talking conductors of channel C¹ through to 115 conductors 79, 80. Consequently when the operator inserts the plug 25 of one of her connecting cord circuits into the answering jack AJ¹, the cord circuit is connected 120 by way of channel C¹ with the calling operator at the distant station. The insertion of plug 25 by the answering operator at the called station closes a circuit from battery through resistance 98, registering sleeve contacts of plug 25 and answering jack AJ¹, conductor 81 and winding of relay 12 to ground. Relay 12 in operating 125 breaks at its left hand armature and back contact the direct connection to ground over 130

which the calling lamp 40 was energized, leaving the lamp connected to ground by way of the winding of relay 49, which relay winding is of high enough resistance 5 to reduce the current flow through the lamp sufficiently to extinguish it. The current flow through the lamp and the relay 49, in series, however, is sufficient to energize relay 49 and hold open the energizing path for 10 lamp 40 by way of the back contact of relay 49, as long as the controlling contact by way of the inner upper armature of relay 10 remains closed. Consequently thereafter the lighting of the lamp 40 is 15 removed from the control of relay 12.

Relay 12 in operating also closes a circuit that extends from battery through the winding of relay 24 (Fig. 5), conductor 89 and outer right hand front contact and armature of relay 12 to ground. The resultant energization of relay 24 energizes the transmitting branch of channel C¹ at the called station. When this occurs, relay 19 in the receiving branch of channel C¹ at 20 the calling station is energized as a result of the energization of the transmitting branch at the called station, and in operating closes the energizing circuit of the associated relay 11 at the calling station. When 25 relay 11 at the calling station operates, the movement of the outer right hand armature of relay 11 breaks the locking path for relay 10 that was initially closed to ground by way of the left hand front contact and armature of relay 12 and closes a locking path for relay 10 directly to ground at the front contact of the outer right hand armature of relay 11. The contacts of the outer right hand armature of relay 11 are 30 so arranged that the front contact closes before the back contact opens, so that ground is maintained continuously upon the locking contact of relay 10, and also upon conductor 88 through which relays 26, 27, 35 36 and 37 are locked up, as will subsequently be explained.

In the condition which now exists, the relays 10 associated with the selected channel at the calling and called stations are energized to extend the channel at these two stations to the associated spring jack terminals, and consequently to the connecting cord circuits at the calling and called stations, plugs of which are inserted in multiple and answering spring jacks respectively, of the channel. The relays 10 at these two stations are maintained energized to keep the respective channel extensions closed subject to the control of the associated relays 11 and 12, relay 11 being held operated 40 as long as a plug is inserted in a channel extension spring jack at the remote station and relay 12 being held energized as long as a plug remains in an associated channel 45 extension spring jack at the local station.

At all the other stations on the toll line the relays 11 of the channel that is in use are held energized to keep the associated guard or busy lamps of the channel illuminated to indicate its unavailable condition 50 and also positively to prevent operators at other stations from gaining access to the busy channel by depriving relay 12 of control over the channel controlling relay 10. At the calling and called stations each of 55 the relays 11 and 12 keeps closed a branch of the energizing circuit of the busy lamps 41 of the associated channel, so that these lamps are not extinguished to indicate the available condition of the channel until the 60 plugs are withdrawn from the channel extension spring jacks at both stations.

The calling and called operators who are now connected over the chosen channel may 65 communicate with each other by connecting their telephone sets 39 through the medium of the respective listening keys 28 with the cord circuits used for extending the connection. The path taken by the outgoing speech is from the operator's set, contacts of key 28, through the repeating coil 37 and plug and jack connection 25, MJ¹, conductors 79, 80, upper front contacts of relay 10, upper back contacts of relay 18, through the inductive coupling of repeating coil 20, back 75 contacts of inner upper and lower armatures of relay 21, conductors 84, 85, potentiometer 113 and transformer 112 to the input side of modulator MC¹. The modulated waves pass through the output transformer 114, adjustable attenuation network controlled by relays 26, 27, filter MFC¹, branch T, and into the line L at the repeating coil 100.

The path of the incoming speech is from 80 coil 100 into receiving branch R, filter DFC¹, attenuating network controlled by relays 36, 37, input coils 116, to the detector input DC¹. The detected speech waves are amplified at AC¹; and are passed through filter 85 LPC¹, and conductors 91, 92 to the bridge terminals of repeating coil 20. From then on to the operator's set the path is the same as that traced for outgoing speech. At the 90 distant selected station the paths for outgoing and incoming speech correspond to those above traced except that the plug 25 of the connecting cord, as stated, is at that station inserted in jack AJ¹. When the operator at the called station learns from the operator at the calling station the particular local connection that is desired, she may 95 complete this connection by inserting the plug 26 of the cord circuit into a multiple jack of the called line and apply ringing current by means of the ringing key 29. The local subscribers at each end of the connection have control over their supervisory lamps 31 through the medium of the associated supervisory relays 32.

- When either operator desires to signal the other for the purpose of disconnecting, or in the supervision of the connection, this may be done by pressing the ringing key 27 of the cord circuit that is being used. As has previously been described in detail, the pressing of ringing key 27 applies ringing current to channel talking conductors 79, 80, thus energizing relay 15, which deenergizes slow-release relay 17, which operates relay 21 to energize the ringing frequency oscillator circuit and apply the 133 cycle current from this source to the outgoing conductors of the transmitting branch of the channel.
- At each of the distant toll stations, including the station with which connection has been established over this channel, the 133 cycle modulation of the channel carrier frequency is detected and amplified, and causes the operation of the relay 18 bridged across the receiving branch of the channel. As previously indicated, the electrical characteristics of the relay 18 and the branch circuit in which it is included are such as to tune the relay and its circuit to be selective of the 133 cycle ringing frequency. The relay 18 at each of the distant toll stations in responding opens the normally closed energizing circuit of and releases relay 16; and the release of relay 16 effects the energization of the associated relay 13. The response of the relay 13 at each one of the distant toll stations applies ringing current from the ringing generator 119 to the channel extension conductors 79, 80. This ringing current is without effect at each distant station except the one that has been selectively called, and since at that station a cord circuit plug 25 is inserted in one of the spring jacks to which conductors 79, 80 extend, the ringing current from generator 119 energizes relay 36 of the cord circuit. This relay upon being energized closes a circuit that extends from battery through supervisory lamp 30, relay 36, and normally closed local contacts of the cord circuit listening key 28 to ground. Consequently the relay 36 is locked up and maintains the lamp 30 illuminated. When the operator responds to the lighting of lamp 30, the breaking of the local contacts in the operation of listening key 28 releases relay 36 and extinguishes lamp 30. Relay 13 of the distant selected station in operating also acts through the medium of relay 14 to disconnect the branch of the talking conductors including relay 15 to prevent any accidental interference of this relay with the continuity of the circuit controlled by the associated relay 17 that would prevent the proper closure of the previously traced energizing circuit of relay 13. Relay 13 also acts through relay 14 to close a short circuit of the series winding of the two-way repeater 20 so as to prevent the condition of unbalance created by the operation of relay 13 from causing the 133 cycle ringing frequency incoming by way of the channel receiving branch to be diverted back to the line by way of the transmitting branch of the channel.
- As has been stated, the application of the 133 cycle ringing frequency to the channel causes the operation of the relay 18, the release of relay 16 and the operation of relay 13 at each of the other toll stations, on account of the normally receptive condition of the channel at each station, whether in use or not. At each of these other stations, the operation of the associated relay 13 connects ringing generator 119 with the conductors that are connected with the two upper armatures of the relay; but as the relays 10 at the non-selected stations are unenergized, the ringing generator is not applied to the channel extension conductors 79, 80 of these stations. However, at the non-selected stations, the operation of relay 14, in response to the operation of the associated relay 13, disconnects relay 15 to prevent any accidental release of relay 17, and consequent operation of relay 21; and also closes the short circuit of the series winding of the associated two-way repeater 20 to prevent the unbalanced condition from communicating the incoming ringing frequency to the transmitting or outgoing branch of the channel and setting up sustained oscillations.
- When the operators take down the connection in response to the display of one or another or both of the supervisory signals 30 and 31 associated with their connecting cord circuits, the removal of the plug 25 from the channel extension spring jack in which it has been inserted breaks the energizing circuit of the associated relay 12 and releases that relay. The release of relay 12 breaks the energizing circuit of relay 24 (Fig. 5), and the consequent release of relay 24 disconnects the plate and filament batteries from the transmitting branch of the channel and effects the withdrawal of the carrier frequency. Upon the withdrawal of the carrier wave, the relay 19 at the other one of the connected toll stations is deenergized and releases associated relay 11. If the plugs at the two connected toll stations are both withdrawn, therefore the relay 12 and the relay 11 are both released. When the relays 11 and 12 at each of the connected stations are released, both branches to ground from conductor 82 are opened, and consequently the busy or guard lamps 41 associated with the multiple jacks M.J. of the corresponding channel are extinguished, thus indicating that the channel is again available for use. The relays 11 and 12 also jointly control the maintained energization of relay 10, the relay 10 being held operated as long as either of the relays 11 and 12 is energized. To prevent the redisplay of the calling lamp 40 in the inter-

val that may occasionally elapse between the release of the relay 12 consequent upon the withdrawal of the plug at the home station and the release of the relay 11 consequent 5 upon the withdrawal of the plug at the distant station, the relay 49 is employed to hold open the energizing branch of the calling lamp 40 to ground by way of the left hand back contact and armature of relay 12 after 10 the relay 12 has once operated. The operation of relay 12 breaks at the above mentioned armature and back contact the normally closed short circuit of relay 49; and 15 that relay in operating opens at its back contact and armature the path to ground through the normal contacts of relay 12 and maintains the path open until relay 10 is finally released. The resistance of relay 49 is such that it limits the current flow to an 20 amount sufficient to maintain relay 49 energized, but not to permit the illumination of lamp 40.

At each of the other toll stations on the line, the relays 19 and associated relays 11 25 are maintained energized as long as the associated carrier channel C¹ is energized. Consequently when both of the operators at the two toll stations between which the connection was established have withdrawn 30 their connecting circuit plugs 25, thus effecting the release of the relay 12 and the associated relay 24 that energizes the transmitting branch of the channel at each of the two stations, the relays 19 and 11 at each of 35 the other stations are released and the busy lamps 41 associated with this channel at the other stations are extinguished to indicate that the channel is again available for use.

40 The foregoing description has been based upon the assumption that the station called was the one requiring the modulation of the 30,000 calling frequency with the 800 cycle station selecting frequency effected by the 45 pressing of key 53 of the operator's station selecting group. If key 52 had been pressed by the operator, relays 4 and 8 would have been energized to modulate the calling frequency with the 600 cycle station selecting 50 frequency; and if key 51 of the group had been pressed, relays 3 and 7 would have been energized to modulate the calling frequency with the 400 cycle station selecting frequency. The selection of these other two 55 stations and the establishment and disestablishment of the connection with them is effected in the same manner as in the case of the selection and connection with the station selectively responsive to the 800 cycle 60 frequency described in the foregoing.

However, as a result of the pressing of the keys 51 and 52 to select their respective corresponding stations, certain other functions are performed which will now be described. In consequence of the performance

of these functions one or more artificial line sections are interposed in the transmitting and receiving branches of the channel to introduce an attenuation adapted to compensate for the less degree of line attenuation which exists between the calling stations and these other stations, which stations are assumed to be less remote than the station selected by the pressing of key 53. We will assume that key 52 is pressed 70 to select a station somewhat less remote or with less intervening line attenuation than the station selected by the pressing of key 53. When key 52 is pressed, relay 4 in operating not only closes a circuit for the energization of the relay 8 to apply the 600 cycle modulating frequency to the calling carrier wave, but it also closes a circuit that extends from battery in parallel 75 through the windings of relays 27 and 37 (Fig. 5), thence by way of conductor 87, outer lower armature and front contact of relay 23, this relay being operated in a manner already described as a result of the pressing of the operator's cord circuit ringing key 27 simultaneously with key 52 and to ground by way of the outer upper armature and front contact of relay 4. Relays 27 and 37 in operating open normal short 80 circuits of the series resistances of the associated artificial line sections, thus including these resistances in the conductors of the transmitting and receiving channel branches respectively, and at the same time close contacts acting to bridge the shunt resistances of the respective artificial line sections across the conductors of the transmitting and receiving branches at the midpoints of the included series resistances. At 85 the same time relay 27 in operating closes 90 at its inner lower front contact and armature a branch circuit to ground by way of the holding conductor 88 which serves to maintain the energization of relays 27 and 37 upon the opening of the initial energizing circuit of these relays when the operator's ringing key 27 and station selecting key 52 are released. The holding conductor 88 extends to ground by way of the outer right hand armature and back contact of relay 11 and the left hand front contact and armature of relay 12, the last 95 mentioned relay being in its energized condition as a result of the presence of plug 25 in one of the channel spring jacks MJ¹. 100 When relay 11 is operated as a result of the energization of the called or distant station transmitting channel branch, in a manner that was previously described, the holding conductor 88 receives its ground directly at the outer right hand armature and front contact of relay 11 instead of by way 105 of the back contact of this armature and the left hand front contact and armature of relay 12, thus continuing the energiza- 110 115 120 125 129

tion of the artificial-line-including relays 27 and 37. The fact that the front contact of the outer right hand armature of relay 11 is closed before the back contact of this armature is opened insures the continuity of the ground connection with the holding conductor 88, so that the relays 27 and 37 are not released by the shifting of the circuit. Consequently after the artificial line sections are included in the transmitting and receiving branches of the channel by the operation of relays 27 and 37 as a result of the selection of the particular station requiring that inclusion, they are maintained in the circuit until the relays 11 and 12 are released by the taking down of the connection at both the calling and the called stations. As has been stated, the result of the inclusion of the artificial line sections is to equalize the transmission gains and insure such attenuation of the transmitted energy as to prevent persistent oscillations or "singing" around the circuit.

When the operator presses key 51 of the station selecting group to operate a signal of the corresponding station on the toll line, relay 3 is operated to apply the 400 cycle modulating frequency to the calling carrier wave. Relay 3 in operating also not only completes the energizing circuit of the relays 27 and 37 previously traced, but also completes a similar energizing circuit for relays 26 and 36. Relays 26 and 36 in operating are locked up to the holding conductor 88 by way of the inner lower front contact and armature of relay 26. Relays 26 and 36 in operating include series and shunt resistance sections in the channel transmitting and receiving branches to increase the attenuation of the energy transmitted from each station in the same manner as was previously described in connection with the operation of the relays 27 and 37 and their associated parts. As a result, when the station corresponding to station selecting key 51 is selected by the pressing of this key and the accompanying operation of relay 3, the relays 27, 37 and 26, 36 are all operated to include two sections of artificial line into each of the channel branches instead of one section only, as when the key 52 was pressed. Consequently in pressing key 51 to select this station, which is assumed to be still closer to the calling station, and therefore, normally to interpose less line attenuation than the station selected by pressing key 52, the apparatus operates automatically to include enough artificial line to hold the transmission gains at a point where standard uniform transmission is ensured and persistent end-to-end oscillations or "singing" around the circuit is prevented.

Instead of arranging the system to provide for the normal exclusion from the chan-

nel transmitting and receiving branches of the artificial line sections, and their automatic inclusion to the extent required in establishing connection with less remote stations, other arrangements to accomplish the same results may be employed without departing from the spirit of the invention.

What is claimed is:

1. In a carrier wave system, a line conductor, three or more stations arranged to communicate thereover, a frequency selective channel having a terminal at each station, means actuated responsive to the use of said channel at any station for impressing a wave on said channel, busy signals associated with said terminals, and means responsive to said impressed wave for operating the busy signals at the distant stations.

2. In a carrier wave system, a line conductor, a plurality of stations arranged to communicate thereover, a frequency selective channel available for use by any two of said stations, means actuated responsive to the use of said channel at any station for impressing high frequency current on said channel, a busy signal associated with the channel at each station, and means responsive to said high frequency current for causing the busy signals at the distant stations to indicate the condition of use or disuse of said channel.

3. In a carrier wave system, a line conductor, three or more stations arranged to communicate thereover, a plurality of frequency selective channels each having a terminal at each station, and a plurality of signals, one for each terminal, means actuated responsive to the use of a channel at any station for impressing high frequency current characteristic of that channel on said channel, and means responsive thereto for operating the busy signals of said channel at the distant stations.

4. In a carrier wave communicating system, a line conductor, three or more stations associated with said conductor, a frequency selective channel having a terminal at each station, operator's means at each station for establishing connection with the corresponding channel terminal, means actuated responsive to the use of said channel at any station for impressing high frequency current on said channel, busy signals associated with said channel at said stations, and means responsive to said high frequency current for causing the distant busy signals to indicate the condition of use or disuse of said channel.

5. In a carrier wave communicating system, a line conductor, a plurality of stations associated with said conductor, a plurality of operators' positions at each station, a frequency selective channel associated with a connection terminal at each operator's position of each station, a plurality of signals

- one for each terminal, means actuated responsive to the use of said channel at any station for operating the associated busy signals at said station, means actuated responsive to the use of said channel at said station for impressing high frequency current on said channel, and means responsive thereto for operating the busy signals of said channel at distant stations.
6. In a carrier wave communicating system, a toll line, a plurality of stations associated with said toll line, a plurality of operators' positions at each toll station, a high frequency communicating channel having an extension at each toll station and a connection terminal at each operator's position of each station, a busy signal associated with each connection terminal, means made operative in establishing connection with said channel by way of the connection terminal at one position for operating the busy signals at the other positions of said station, means also actuated in establishing said connection for impressing high frequency current on said channel, and means responsive thereto for operating the busy signals at the distant stations.
7. In a carrier wave communicating system, a toll line, three or more stations associated with said toll line, a frequency selective channel having a terminal at each station, means actuated in establishing connection therewith at any of said stations for applying high frequency current to said channel, and means responsive to said high frequency current for giving an indication of the use of said channel at each of the other stations.
8. In a carrier wave communicating system, a line having a plurality of high frequency channels associated therewith, a plurality of stations, a terminal for each channel at each station, means at each station for establishing connection with any of said channels, means actuated in establishing such connection for impressing high frequency current on said channel, and means actuated thereby for indicating the busy condition of the corresponding channel at the distant stations.
9. In a carrier wave communicating system, a toll line, a calling station and a called station associated with said line, a high frequency communicating channel having a connection terminal and associated busy signal at each station, means for applying high frequency current to said channel upon connection being made therewith, a calling signal at said called station, means under the control of said calling station for operating said calling signal at the called station, and means responsive to the application of said high frequency current for operating said busy signal at the other station.
10. In a carrier wave communicating system, a toll line having a high frequency communicating channel associated therewith, a plurality of stations on said toll line, a terminal for said channel at each of said stations, means for applying high frequency current to said channel upon connection being made therewith, a calling signal and a busy signal associated with each terminal, and means made operative in establishing connection with the terminal at one of said stations for rendering operative the calling signal at any desired one of the distant stations and means responsive to the application of said high frequency current for operating the busy signal at each of the other distant stations.
11. In a carrier wave communicating system, a toll line, three or more stations associated therewith, a multiple terminal frequency selective channel having a terminal at each station, busy indicating means and a calling signal associated with each terminal, and means made operative in establishing connection with one of said channel terminals for applying high frequency current thereto, means responsive to said current for operating the busy indicating means at the distant stations, means for selectively operating a particular distant one of said calling signals, and means also actuated upon connection with said channel terminal for operating the busy indicating means of the terminals at the calling station.
12. In a carrier wave communicating system, a line conductor, three or more stations associated therewith, a high frequency communicating channel having a terminal at each station, means for impressing high frequency current on said channel, a calling signal associated with the channel terminal at each station, an operator's connecting circuit for establishing connection with said channel by way of the terminal thereof, and means including an operator's connecting circuit key for controlling said high frequency current selectively to operate the calling signal of any desired one of the other stations.
13. In a carrier wave communicating system, a line conductor, three or more stations associated therewith, a high frequency communicating channel having a terminal with an associated calling signal at each station, a connecting circuit at each station for establishing connection with said channel, and means including a switch exercising control through said connecting circuit for selectively operating the calling signal of the channel at any desired distant station.
14. In a carrier wave communicating system, a toll line, three or more stations associated therewith, a high frequency communicating channel having a terminal and associated calling signal at each station, a plurality of connecting circuits at each sta-

- tion any one of which may be used to establish connection with said channel, an individual key for each connecting circuit, a key common to a group of connecting circuits, a high frequency calling channel controlled by said common key and having a selectively responsive branch at each station, and means under the joint control of said common key and the individual key of the connecting circuit through which connection is established for selectively operating the calling signal at any desired one of the other stations.
15. In a carrier wave communicating system, a line conductor, three or more stations associated therewith, a high frequency communicating channel having a connection terminal at each of said stations, a calling signal associated with each connection terminal, an electrically actuated switch at each station adapted when operated to establish operative relation between said channel and the associated connection terminal, and means at each station for selecting and operating the calling signal and associated electrical switch of any desired one of the other stations.
16. In a carrier wave communicating system, a line conductor, a plurality of stations associated therewith, a high frequency communicating channel having a connection terminal at each station, said channel being in normally inoperative relation with said connection terminals, and means operated in establishing connection at a connection terminal for placing said connection terminal in operative relation with said channel.
17. In a carrier wave communicating system, a line conductor, a plurality of stations associated therewith, a high frequency communicating channel having a connection terminal at each station, means at each station for impressing high frequency current on said channel, and means responsive thereto for preventing the establishment of operative relation between said channel and its connection terminals at certain other of said stations.
18. In a carrier wave communicating system, a line conductor, three or more stations associated therewith to communicate thereover, a high frequency communicating channel having an associated connection terminal at each station, means for impressing high frequency current thereon, said channel being normally disconnected from the associated connection terminals, means made operative in establishing connection with a connection terminal for connecting said connection terminal with said channel, and means operated by said high frequency current for preventing the operation of said last mentioned connecting means made operative by the completion of connection with said channel at another of said stations.
19. In a carrier wave communicating system, a line conductor, a plurality of stations associated therewith, a high frequency communicating channel having a normally disconnected connection terminal at each station, means made operative in establishing connection with the channel connection terminal at any station for connecting the channel with the terminal at that station and means for impressing high frequency current on said channel, and means responsive to said high frequency current for preventing its connection with the terminals at the other stations.
20. In a carrier wave communicating system, a line conductor, a plurality of stations associated therewith, a high frequency communicating channel having a normally disconnected connection terminal at each station, means for impressing high frequency current on said channel, means made operative in establishing connection with the channel connection terminal at any station for connecting the channel with the terminal at that station, means responsive to said high frequency current for preventing its connection with the terminals at the other stations, and station selecting mechanism under the control of said station for connecting said channel with the connection terminal of a particular selected one of said other stations.
21. In a carrier wave communicating system, a line conductor, a plurality of stations associated therewith, a high frequency communicating channel having a normally disconnected connection terminal at each station, means for impressing high frequency current on said channel, means made operative in establishing connection with the channel connection terminal at any station for connecting the channel with the terminal at that station, means responsive to said high frequency current for preventing its connection with the terminals at the other stations, and station selecting mechanism under the control of said station for connecting said channel with the connection terminal of a particular selected one of said other stations, and signal apparatus at said selected station operated upon the selection thereof.
22. In a carrier wave communicating system, a line conductor, a plurality of stations associated therewith, a high frequency communicating channel having a connection terminal at each station in noramlly inoperative relation with said channel, means for impressing high frequency current on said channel, means for controlling said current in accordance with the desired station, and means responsive thereto for placing said channel in operative relation to the terminal thereof.
23. In a carrier wave communicating system, a line conductor, a plurality of stations

associated therewith, a high frequency communicating channel having a connection terminal at each station in normally inoperative relation with said channel, means for impressing high frequency current on said channel, a calling signal associated with each connection terminal, means at the calling station for controlling said high frequency current, and means responsive thereto for placing said channel in operative relation with the connection terminal and operating the associated calling signal at any desired one of the other stations.

24. In a carrier wave communicating system, a line conductor, a plurality of stations associated therewith, a high frequency communicating channel having a connection terminal at each station, a high frequency calling channel having controlling and responsive apparatus at each station, and means controlled by a calling station through the medium of the controlling and responsive apparatus of said calling channel for excluding said communicating channel from operative relation with all connection terminals excepting those of the calling and called stations.

25. In a carrier wave communicating system, a line conductor, a plurality of stations associated therewith, a high frequency communicating channel having a normally disconnected connection terminal at each station, a high frequency calling channel having controlling and responsive apparatus at each station, and means controlled through the medium of the controlling and responsive apparatus of said calling channel for selectively connecting said communicating channel with its connection terminal at a particular one of said stations.

26. In a carrier wave communicating system, a line conductor, a plurality of stations associated therewith, a high frequency communicating channel having a normally disconnected connection terminal at each station, a high frequency calling channel having controlling and responsive apparatus at each station, means controlled through the medium of the controlling and responsive apparatus of said calling channel for selectively connecting said communicating channel with its associated connection terminal at a particular one of said stations, and means controlled over the communicating channel for preventing the connection of said communicating channel with its connection terminals at other stations.

27. In a carrier wave communicating system, a line conductor, a plurality of stations associated therewith, a high frequency communicating channel having a normally disconnected connection terminal at each station, a high frequency calling channel having controlling and responsive apparatus at each station, means controlled through the

medium of the controlling and responsive apparatus of said calling channel for selectively connecting said communicating channel with its associated connection terminal at a particular one of said stations, means controlled by the communicating channel for preventing the connection of said communicating channel with its connection terminals at other stations, a busy signal associated with each connection terminal, and means for controlling said busy signal made operative in the operation of the aforesaid means for preventing the connection of said channel with the associated connection terminal.

28. In a carrier wave communicating system, a line conductor a plurality of stations associated therewith, a high frequency communicating channel having at each station an extension in normally inoperative relation with said channel, a high frequency calling channel, and mechanism at each of said stations under the joint control of said communicating channel and said calling channel for effecting the operative relation of said communicating channel with its extension at any desired one of said stations.

29. In a carrier wave communicating system, a toll line, a plurality of stations associated with said line, a high frequency communicating channel having a normally disconnected extension at each station, a calling signal associated with each extension, a high frequency calling channel, and means under the joint control of said communicating channel and said calling channel for effecting the connection of the extension and the selective operation of the calling signal at any desired one of said stations.

30. In a carrier wave communicating system, a line conductor, a plurality of stations associated therewith, a high frequency communicating channel having a terminal at each station, an electrically actuated switch and energizing circuit therefor at each station for controlling the operative relation of the associated terminal with said channel, means for energizing said channel, and means at each station responsive to the energization of said channel for controlling the energizing circuit of said electrically actuated switch.

31. In a carrier wave communicating system, a line conductor, a plurality of stations associated therewith, a high frequency communicating channel having a terminal at each station in normally inoperative relation with said channel, an electrically actuated switch at each station for placing the associated terminal in operative relation with said channel, an energizing circuit for said switch normally under the control of the terminal at the associated station, and means operated in establishing connection with the terminal of said channel at a distant station for transferring the control of

said energizing circuit from the terminal of the associated station to controlling apparatus at said distant station.

32. In a carrier current transmission system, a line having three or more stations, channels superposed on said line and terminating in each of said stations, a plurality of operators' positions at each station, multiple connecting terminals on said positions for each channel, and means actuated when an operator makes connection with any channel terminal for indicating the channel as busy at the other terminals of said channel in each of said stations. 70
33. In a carrier current transmission system, a line having three or more stations, channels superposed on said line and terminating in each of said stations, connection terminals for each channel at each station for gaining access to a channel, selective calling arrangements at one station for selecting a desired distant station comprising a calling-frequency wave-generator and a source of communicating waves, means at each distant station responsive to the communicating wave sent out from said one station for locking the channel over which said communicating wave is sent against access by any of said distant stations, and means at the particular distant station being selected responsive to the calling wave for rendering the channel over which said communicating wave is being sent accessible at said station. 85
34. In a carrier current transmission system, a line having three or more stations, channels superposed on said line employing different frequencies and terminating at said stations, means at one station for transmitting waves of the different channel frequencies, and means responsive to waves transmitted over one channel for selecting a desired distant station and responsive to waves sent over another channel for rendering said last-mentioned channel inaccessible to the distant stations other than the selected one and at the selected station for cooperating with the station-selecting means to render the last-mentioned channel accessible at the selected station. 100
35. In a multiplex carrier wave transmission system, a high frequency communication channel, a second high frequency channel, a sending station, and a plurality of distant stations, said channels having access to all of said stations, means at the sending station to appropriate said communication channel for use and to send a high frequency wave thereover to the distant stations, signals at the distant stations actuated by said high frequency wave to indicate that said communication channel has been taken for use, calling signals at said distant stations, means to send a wave of characteristic frequency over said channel dependent upon the station to be communicated with, and means for actuating the calling signal at the distant station to be communicated with and only at that station, under the control of the wave sent over said second channel. 115
36. In a multiplex carrier wave transmission system, a plurality of high frequency communication channels employing each a wave of different frequency for transmission, a common calling channel, a sending station and a plurality of distant stations, said channels being accessible to all of said stations, and means to call a desired distant station for communication over a certain channel comprising means to send a carrier wave of the particular communication channel and means to send over the calling channel a wave of characteristic frequency to indicate the desired station, and a calling signal at the desired distant station for the particular communication channel to be used, said signal being operated by the joint action of said two transmitted waves. 125
37. In a carrier wave transmission system, a plurality of communication channels employing each a wave of a definite channel frequency, a common channel, stations common to all of said channels, a device for each channel at each station, and means to actuate selectively a single particular device comprising means to transmit to all of said stations a wave of selected channel frequency, and means to transmit over the common channel a wave of characteristic frequency to exert a control at only the selected distant station, said two transmitting waves conjointly actuating said single device. 140
38. In a carrier transmission system, stations, communication channels common to said stations, said channels when in deenergized condition being accessible by any station, means to energize a channel and render said channel accessible by any of said stations, means to transmit over another channel a wave of characteristic frequency, and means at said desired station only, responsive to said wave of characteristic frequency for rendering said energized channel accessible by said desired station only. 155
39. In a carrier wave communicating system, a line having three or more carrier stations, carrier wave channels superposed on said line and terminating in said stations, sending apparatus for a channel at a station comprising means for selectively calling any other station to which the channel has access, said means including station keys and one or more wave producing circuits for waves having distinctive calling frequencies, said line having included therein an attenuating network made up of sections, relays for cutting in or out certain sections, 170

- tions, control circuits for said wave producing circuits and for said relays extending from said keys whereby when a particular key is depressed to control a particular 5 wave-producing circuit to send a particular wave for establishing selective communication with a desired distant one of said stations, one or more of said relays is controlled to include an amount of attenuation 10 in said line dependent upon the station with which communication is being established.
40. In a carrier current telephone system, a line terminating in jacks, a carrier fre-

quency generating and modulating means including an electron discharge tube for supplying speech modulated waves for speech transmission, an energy supply circuit for said tube, local connecting circuits having plug terminals, and a circuit completed upon the insertion of a plug into one of said 15 jacks for closing the energy circuit for said tube. 20

In witness whereof, I hereunto subscribe my name this 27th day of March, A. D. 1922.

SAMUEL B. WILLIAMS, JR.
